Primary Examiner — Brett Miller*Assistant Examiner* — Jessica M Gebhart(74) *Attorney, Agent, or Firm* — Seth M. Reiss(57) **CLAIM**

I claim the ornamental design for an adjustable roll-on stand, substantially as shown and described.

DESCRIPTION

FIG. 1 is a top perspective view of the adjustable roll-on stand of the subject invention with parts shown separated. FIG. 2 is a bottom perspective view of the roll-on stand of the subject invention with parts assembled.

FIG. 3 is a top plan view of the roll-on stand with parts shown separated.

FIG. 4 is a bottom plan view of the roll-on stand with parts assembled.

FIG. 5 is a left side view of the roll-on stand with parts shown separated.

FIG. 6 is a right side view of the assembled roll-on stand illustrating its use in conjunction with a vehicle and an umbrella with pole.

FIG. 7 is a front view of the roll-on stand with parts shown separated; and,

FIG. 8 is a back view of the roll-on stand of the subject invention with parts assembled.

The broken lines shown depict environment that form no part of the claimed design.

1 Claim, 6 Drawing Sheets(56)
